UNITED STATES PATENT OFFICE.

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS.

BOBBIN.

Application filed November 27, 1923. Serial No. 677,311.

To all whom it may concern:

Be it known that I, FRANK MOSSBERG, a citizen of the United States, residing at Attleboro, in the county of Bristol and State of Massachusetts, have invented certain new and useful Improvements in Bobbins, of which the following is a specification.

This invention relates to an improved construction of yarn package holder, such package being usually in the form of a cop or bobbin and the holder being more particularly employed for supporting a package on a carrier in a braiding machine; and the object of this invention is to provide a package holder of simple and practical construction having resilient means on its body portion for yieldingly gripping or binding a cop or bobbin tube when positioned thereon to prevent the bobbin from relative rotation.

With these and other objects in view, the invention consists of certain novel features of construction, as will be more fully described, and particularly pointed out in the appended claims.

In the accompanying drawings,

Figure 1 is a side elevation showing a cop in section as positioned on my improved holder.

Figure 2 shows a piece of sheet metal cut to provide longitudinal ribs therein and adapted to be folded or shaped to form a bulbous sleeve with bow-shaped ribs.

Figure 3 shows the metal strip as folded or bent into the desired shape.

Figure 4 is a plan view of the holder with the sleeves on the body portion thereof.

Figure 5 shows a modified construction wherein a strip of metal is split to form ribs or fingers thereon which are joined together at one end only.

Figure 6 illustrates the strip of metal as bent into sleeve form.

Figure 7 illustrates a pair of these sleeves of modified construction, as being mounted on the body portion of a yarn package holder.

Figure 8 is another modified construction illustrating the sleeves as formed of wire bent into helical coils to provide circular ribs for yieldably gripping and retaining the package tube on the holder.

It is found in practice of advantage to

provide in a yarn package holder means for yieldingly gripping the interior surface of the paper cop tube of the yarn package so as to prevent it from rotating on the bobbin during the drawing of the yarn therefrom and also to permit the cop to be quickly positioned on the bobbin and as readily withdrawn therefrom when desired; and the following is a detailed description of means whereby these advantageous results may be accomplished:—

With reference to the drawings, 10 designates the base or head of my improved holder which may be in any desired form, the same being usually provided with teeth 11 or other means to be engaged by the latch of the braider carrier.

This head is provided with a body portion 12 preferably constructed of sheet metal folded or rolled into tubular form with one of its ends securely held by brazing or other suitable means into said head.

In order to provide resilient or flexible means on this body portion for yieldingly gripping the cop tube when positioned thereon, I have cut a strip of metal from sheet stock as best illustrated in Figure 2, and in this strip of metal I have formed a multiplicity of longitudinally-disposed, spaced-apart ribs or arms 13 connected at their top and bottom ends to the framework of the strip.

This strip of metal is then bent into sleeve form and the arms or ribs are bowed outwardly as best illustrated in Figure 3, forming a bulbous body with collars 14 and 15 at its upper and lower ends to which the opposite ends of these arms or ribs 13 are connected. I next secure a pair of these sleeves to the tubular body 12 of the holder preferably in spaced-apart relation, that is, one being near the upper end of the body and the other being near the bottom or head end of the tube.

Each of these sleeves is fastened to the body portion in such a manner that the positioning and removing of the cop from the bobbin may be readily effected. I may fasten as by brazing one end of the sleeve to the body and leave the opposite end loose and free to receive a relative movement on the body as the arms are contracted and expanded due to the positioning and removing of the cop tube 16 on which is wound the

yarn 17. I also may secure the sleeve upon the body portion by providing short slots or grooves as 21 and 22 in the body portion and forming detents 23 and 24 on the inner surface of the sleeve for projecting into these slots 21 and 22. The slots or grooves being so spaced apart that the detent 23 on the end of the sleeve will engage the end 25 of the slot 21 upon the position of the cop on 10 the bobbin before the detent 24 on the inner end of the sleeve engages the end 26 of the slot 22, thereby leaving room for the lengthening of the sleeve. When the cop is removed the reverse action is true the inner 15 end of the sleeve being held by detent 24 permitting the outer end of the sleeve to lengthen longitudinally. By this construction, it will be seen that the positioning or removing of the cop will tend to lengthen 20 the sleeve longitudinally and decrease its diameter thereby facilitating the positioning or removing of the cop.

By this construction of mounting these sleeves in spaced-apart relation on the tubular body of the holder the device is made very strong and durable and yet is provided with flexibility necessary for the secure fastening of the yarn package on the holder.

Instead of connecting these ribs at both 30 ends as above described, in some cases I split the strip and form a sleeve as illustrated in Figures 5, 6 and 7, in which the lower ends 18 of the ribs 19 are free or disconnected from each other.

35 In still other cases, I coil a wire 20 into a sleeve form as best illustrated in Figure 8 and secure one end 27 of each coil to the body 12.

By this construction of resilient sleeve of 40 wire coils the ends of the sleeve are caused to expand when the cop tube is given a relative rotating motion in one direction, and is caused to contract by a relative rotation in the opposite direction, whereby the clinging 45 or gripping effect of the sleeve upon the package tube may be adjusted somewhat.

My improved yarn package holder is very simple and practical in construction and effective in its operation and by its use a yarn 50 package may be quickly positioned thereon, held firmly in that position and as quickly removed when desired.

The foregoing description is directed

solely towards the construction illustrated, but I desire it to be understood that I reserve 55 the privilege of resorting to all the mechanical changes to which the device is susceptible, the invention being defined and limited only by the terms of the appended claims.

60 I claim:

1. A yarn package holder having a spindle, a pair of spaced sheet metal sleeves thereon each having one end secured to said spindle and each having a plurality of 65 spring ribs for engaging and yieldingly securing a yarn package to the spindle.

2. A yarn package holder having a spindle, a head secured to one end thereof, a pair of sheet metal sleeves arranged in 70 spaced relation along the length of said spindle and each having one end secured thereto and each sleeve having spaced spring bow-shaped ribs for engaging and yieldingly securing a yarn package to the holder.

75 3. A yarn package holder comprising a body portion formed of a pair of spaced packages gripping sleeves, each having resilient bow-shaped ribs, a tubular member connecting said sleeves, a head-member, and 80 means for connecting said sleeves to said head.

4. A yarn package holder having a tubular body portion, a head secured to one 85 end thereof, and a pair of sleeves on said body portion located adjacent the opposite ends thereof, each having yielding ribs for securing a yarn package on said holder.

5. A yarn package holder having a tubular body portion, a head secured to one 90 end thereof, and a pair of spaced sleeves on said body portion, each having spaced longitudinally-disposed yielding bow-shaped ribs for securing a yarn package on said holder.

95 6. A yarn package holder having a tubular body portion with slots therein, a head secured to one end thereof, a sleeve secured at one end to said body and free at its opposite end, a projection on said free end 100 slidable in said slot, said sleeve having longitudinally-disposed bow-shaped resilient ribs for engaging and yieldingly retaining a yarn package thereon.

In testimony whereof I affix my signature.

FRANK MOSSBERG.
